UNITED STATES PATENT OFFICE.

WILLIAM BROWN WILSON, OF WELL-HALL, ENGLAND.

SINGLE SLEEVE VALVE FOR INTERNAL-COMBUSTION ENGINES, STEAM ENGINES, AND THE LIKE.

Application filed October 15, 1924. Serial No. 743,734.

To all whom it may concern:

Be it known that I, WILLIAM BROWN WILSON, a subject of the King of England, and a resident of No. 14 Dickson Road, Well-Hall, S. E. 9, in the county of Kent, Kingdom of Great Britain, have invented certain new and useful Improvements in Single Sleeve Valves for Internal-Combustion Engines, Steam Engines, and the like, of which the following is a specification, reference being had to the accompanying drawings.

The present invention relates to single sleeve valves for internal combustion engines, steam engines and the like, the principal object of the invention being to provide a novel and simple form of single sleeve valve which can be conveniently operated so as to be positive in action and is effective to present a large port area for the admission and emission or exhaust of the working fluid, a condition which is essential for satisfactory operation of high speed engines, insuring, as it does, high volumetric efficiency at such speeds.

Further objects, advantages and novel features of design, construction and arrangement comprehended by the invention will be apparent as the nature thereof is better understood from the following description of one embodiment of the invention which I have illustrated on the accompanying drawing forming a part hereof.

In said drawing Fig. 1 is a fragmentary vertical central section through the cylinder of an engine constructed in accordance with my invention, and Fig. 2 is a fragmentary horizontal section on line 2-2 in Fig. 1 looking in the direction of the arrows. Like symbols are used to designate the same parts in both figures.

As shown, the engine comprises the usual cylinder block 1 disposed on the crank case 2 which encloses the crank shaft 3 connected by the connecting rod 4 with the piston 5 in the usual manner, the cylinder block being arranged to provide a space or chamber 6 for the circulation of cooling water and the interior of the block being bored out to form the cylinder 7.

Within the cylinder 7 and forming a working fit therein I dispose a sleeve 8 which, adjacent the upper end of the cylindrical portion and above the upper end of the block,

is increased in diameter so as to form a flange or rim 8' which outwardly overhangs and rests on the upper end of the block. From the perimeter of the flange the outer surface of the sleeve is curved inwardly and upwardly at at 8" to finally merge into a spindle 10, the form of curve given to the sleeve head between the flange 8' and the spindle being preferably that known as the tractrix or Schiele's curve. A cylinder head 11 is removably secured upon the upper end of the cylinder block and arranged to provide an internal chamber 12 for the circulation of cooling water and the spindle 10 is extended upwardly through a suitable bore in the head and terminates thereabove.

The sleeve is machined internally in its cylindrical portion to receive the piston 5 and also above its cylindrical portion to form the combustion space or chamber above the piston which chamber is similar in shape to the adjacent exterior of the head of the sleeve and in this portion of the sleeve a plurality of suitable ports 13 are provided, preferably three in number (see Fig. 2). Through these ports, which are preferably symmetrically spaced about the head, the working fluid, such as the combustible mixture employed in internal combustion engines, is admitted to the combustion chamber and cylinder during the inlet stroke of the piston and a portion thereof exhausted during the exhaust stroke thereof after having been burned therein.

The interior surface of the cylinder head 11 is also suitably machined and finished to conform to the outer surface of the head of the sleeve so as to form a gas tight fit therewith and the end of the spindle 10 projecting above the cylinder head is interiorly bored and threaded to receive a spark plug 15, the bore being extended centrally downward in the head to terminate at the upper end of the combustion chamber.

The cylinder head is provided with a plurality of ports, preferably four in number, designated at 16-16, 17-17, said ports being formed in the wall thereof which lies adjacent the head of the sleeve and extending outwardly therefrom to the exterior of the head for connection at that point to suitable pipes or manifolds. For convenience of description, the ports 16 may be con-

sidered as the inlet ports and the ports 17 as the exhaust ports, but obviously these relations may be reversed if desired. It will be noted that the disposition of the ports where they pass through the cylinder head walls is such that they extend in a more or less radial direction with respect thereto and that the general direction of the passages respectively leading from the ports is such that streams of fluid simultaneously entering the cylinder on the inlet stroke from either the ports 16-16 or 17-17 will converge upon each other, giving rise to the effect known as "turbulence" which is of advantage in increasing the efficiency of the engine particularly at low speeds.

The shape of the several ports to which reference has just been made may preferably generally conform to that of an isosceles triangle whose base, disposed normal to the axis of the cylinder, is substantially one-half the height of the legs but under certain conditions it may be found desirable to somewhat modify the form of port employed, it being, however, understood that ordinarily the shape and area of the various ports in the sleeve and in the cylinder head will be substantially similar to each other.

I also preferably provide an auxiliary port 18 in the sleeve toward the lower end thereof and at a position to be uncovered by the piston 5 as it approaches the lower end of its stroke and a corresponding port 19 in the cylinder wall disposed to register therewith, these ports being operative to permit a certain amount of the exhaust gases to pass out of the cylinder toward the end of the exhaust stroke with resulting reduction in internal pressure in the cylinder before the sleeve is oscillated by suitable actuating mechanism.

A preferred form of mechanism for effecting oscillation of the sleeve forms the subject of and is claimed in a separate application for Letters Patent of the United States executed by me of even date herewith and entitled Improvements in mechanism for operating single sleeve valves for internal combustion engines, steam engines and the like, Serial Number 743,735, and extended description thereof herein is therefore omitted, it being sufficient for the purposes of this application to say that said mechanism through the medium of a gear 20 disposed on the projecting end of the spindle 10 and suitably connected with a vertical shaft 20' actuated from a cam shaft 21 disposed in the crank case, is operative at properly timed intervals to effect an oscillation of the sleeve in the horizontal plane so as to bring two of the ports in its head into registry either with the ports 16 or the ports 17 and thus permit the admission or exhaust of the gases or other working fluid to or from the cylinder.

This sleeve actuating mechanism is preferably so timed with respect to the movement of the piston that during the major portions of the compression and power strokes of the latter all of the ports 16 and 17 are closed (see Fig. 2), while during the inlet and exhaust strokes the sleeve is rotated through an angle preferably approximating 31°, first in one direction and then in the opposite direction, thus bringing two of the ports 18 opposite the ports 16 or the ports 17 at each oscillation of the sleeve, thereby admitting the gases to or allowing them to escape from the cylinder. As hitherto stated, the auxiliary exhaust ports 18 and 19 are effective to permit the escape of a certain quantity of the exhaust gas as the piston approaches the lower end of its power stroke, these ports, then coincident with each other, being uncovered by the piston and the sleeve having not as yet commenced its movement of oscillation from the piston shown in Fig. 2, but as the piston approaches the lower end of the inlet stroke and thereby uncovers the port 18, the escape of the fresh gases therethrough is prevented since as the sleeve has been oscillated in the opposite direction to open the inlet ports during this stroke and thereby permit the admission of the gas, the port 18 has traveled away from the port 19 which is thus covered by the body of the sleeve with consequent prevention of the escape of the fresh gases.

It will thus be apparent that through the medium of my invention it is possible to attain by means of a single sleeve having a movement through but a small angle and in a single plane, a very rapid opening and closing of the inlet and exhaust ports as well as ports of maximum area with consequent marked increase in volumetric efficiency; that I am enabled to so locate the spark plug or other ignition means as to prevent detonation and insure the rapid propagation of flame throughout the compressed gases; that I provide a combustion chamber of ideally efficient shape, without pockets, containing no mass of metal liable to become overheated with consequent overheating and possible distortion of the parts, and that the whole of the sleeve head is in continual contact with the water jacketed cylinder head wall with consequent adequate dissipation of the surplus heat.

It will, of course, be understood that my invention is equally well adapted for use in multi-cylinder as in single cylinder engines and further that while I have herein illustrated and described one form of the invention with considerable particularity I do not thereby desire or intend to confine myself specifically thereto as the design, construction and arrangement of the various parts are capable of material modification from the precise embodiments to which I

have referred without departing from the spirit and scope of the invention as defined in the appended claims.

Having thus described my invention, I claim and desire to protect by Letters Patent of the United States:

1. An engine comprising a cylinder having a terminal exhaust port in its wall, a cylinder head and a sleeve disposed partially within the cylinder and partially within the head, that portion of the valve disposed in the cylinder comprising a port adapted to register with said exhaust port and that portion of the valve above the cylinder being increased in diameter adjacent thereto to provide an overhanging flange seating on the end of the cylinder and then curved upwardly and inwardly to merge into a cylindrical spindle extending through the head.
2. An engine comprising a cylinder having a terminal exhaust port in the lower part of its wall, a cylinder head and a sleeve disposed partially within the cylinder and partially within the head, that portion of the sleeve disposed within the cylinder having a port adapted to register with said terminal exhaust port and that portion of the sleeve within the head being of greater diameter at its base than the cylinder and thence upwardly and inwardly curved and provided with a plurality of ports and the cylinder head being also provided with ports adapted for registration with the ports in the sleeve.
3. An engine comprising a cylinder, a cylinder head, a piston and an oscillatory sleeve extending in the cylinder and in the head and in which the piston is adapted to reciprocate, that portion of the sleeve in the head being curved upwardly and in-

wardly and provided with a plurality of ports adapted to register with ports in the head, said sleeve being provided near its lower end with an auxiliary exhaust port and said cylinder having a port adapted to register therewith, and means for effecting oscillation of the sleeve.

4. An engine as specified in claim 10 and in which the auxiliary exhaust port is so positioned as to be uncovered by the piston toward the lower end of its stroke.

5. An engine as specified in claim 10 and in which said sleeve oscillating means are so timed that the auxiliary port in the sleeve will register with the auxiliary port in the cylinder when the piston approaches the lower end of its power stroke and will be out of registry therewith when the piston approaches the lower end of its inlet stroke.

6. An engine having a cylinder having an auxiliary exhaust port in its wall, a removable cylinder head having a plurality of ports and an oscillatory sleeve disposed in the cylinder and extending into the head, said sleeve having a port adapted to register with said auxiliary exhaust port and being provided with an overhanging flange adapted to rest on the upper end of the cylinder and being upwardly and inwardly curved from said flange and provided with a plurality of ports in said curved surface adapted to register with the ports in the head, the interior of said head being formed to coincide and form a gas tight fit with said surface, and means for oscillating said sleeve within the cylinder and the head so as to move the ports into and out of registry.

In witness whereof, I have hereunto set my hand this 2nd day of October, 1924.

WILLIAM BROWN WILSON.
